UNITED STATES PATENT OFFICE

150,355

DESIGN FOR A LAMP

David M. Golden, Chicago, Ill.

Application December 7, 1946, Serial No. 135,335

Term of patent 3½ years

(Cl. D48—20)

To all whom it may concern:

Be it known that I, David M. Golden, a citizen of the United States, residing at Chicago, in the county of Cook and State of Illinois, have invented a new, original, and ornamental Design for a Lamp, of which the following is a specification, reference being had to the accompanying drawing, forming a part thereof.

In the drawing:

Fig. 1 is an elevational view of a lamp, showing my new design.

Fig. 2 is a top plan view on a reduced scale of the lamp of Fig. 1.

I claim:

The ornamental design for a lamp, as shown.
DAVID M. GOLDEN.
